UNITED STATES PATENT OFFICE.

ANDRÉ BECHLER, OF MOUTIER, SWITZERLAND.

GEAR-WHEEL PUMP.

Application filed November 13, 1925, Serial No. 68,913, and in Switzerland November 18, 1924.

The present invention relates to a gear wheel pump adapted for producing by a simple arrangement a considerable pressure and provided with means for changing the 5 output. For this purpose the distance between the centers of the gearing wheels is adjustable or made variable.

In certain manufacturing as for instance in the manufacture of artificial silk pumps 10 are required developing a considerable pressure and delivering always the same quantity quite independently from the tightness of parts or of the number of draw plates to be fed. In order to fulfill such conditions 15 pumps having a plurality of pistons of a variable stroke have been proposed. But such pumps in order to secure the constancy of the pressure must have a large number of pistons which necessitates a certain succession 20 of the working strokes so as to secure a continuous running. Such pumps are therefore easily injured and expensive and never give a good continuity of output.

It is the object of the present invention to 25 propose a pump free of all such defects.

In the accompanying drawing two working examples of a pump according to the invention are shown.

Fig. 1 is a side elevation with cover 30 removed of a first working form, and

Fig. 2 a vertical section on line II—II in Fig. 1,

Fig. 3 is a plan of the second form,

Fig. 4 a section on line IV—IV of Fig. 5 35 and

Fig. 5 a section on line V—V of Fig. 3.

The pump represented in Figures 1 and 2 possesses an open box 1 closed by a cover 2. The box is supporting a trunnion which is 40 integral with a rotative bracket 3 and carries on the outside of the box an arm 4. Bracket 3 embedded in a cavity on the inside of box 1 supports one pinion 5 of the two pinions of the pump. The axis of rotation 45 of this pinion 5 does not correspond with the axis of the rotative bracket 3 but is arranged eccentrically so that, when the latter is turned, said pinion is withdrawn from or approached to the center of the second pinion 6 likewise embedded within a cavity of box 1. The axis of this second pinion crosses the cover 2 and carries the outside pinion 7 by means of which the pump is 50 operated. As seen from Fig. 1 the rotative bracket 3 partly surrounds the pinion 5 tightly so that the latter moves as if it was

embedded within a cavity of the box like pinion 6.

This pump works like the usual gear wheel pumps. The gear wheels turn in the direction of the arrows in Fig. 1 and the liquid is introduced through a canal 8 and delivered through a canal 9 after having passed between the teeth of the pinions. If by means of a rocker arm 4 moving in the face of a 60 division the bracket 3 is swung so as to change the distance between the centers of the two pinions the teeth of the two gear wheels allow a certain quantity of the liquid to reflow again to the suction side whereby 65 the output of the pump is diminished. In this way the output of the pump may be changed according to the eccentricity between the axis of the pinion 5 and the axis of the bracket 3.

It is clear that instead of one arm 4 any other device could be mounted on the axis of bracket 3 for instance the wheel of a worm gear so that the change of eccentricity could be as small as possible.

In the second working form according to the Figures 3, 4 and 5 there is a casing 10 open on both sides and enclosed between a cover 20 and a block 30. To the latter are attached two tie rods 40 which are holding 85 a cross bar 50. A pressure screw 60 passing through the center portion of said cross bar and bearing on the cover 20 presses the casing 10 against the block 30 with a tight fit. A pinion 80 turns freely within a cavity 70 of said casing and is guided at its periphery by said cavity. This pinion 80 gears with a pinion 90 which turns round a stationary trunnion and which is integral with a shaft 100 lodged within the block 30 and 95 is extended to the outside where it carries a rope pulley 110 for driving the pump. The pinion 90 turns within a cavity of an adjustable segment 120 having the same thickness as the casing 10 and the pinions 80 and 90. A pin 130 maintains this segment and with it pinion 90 in a given position and guides the casing 10 while this casing is 100 swung by means of the screws 140 which pass across swellings of the rods 40. These 105 screws bear on lugs 160 cast to the casing 10. The liquid is introduced by means of a canal 170 within block 30 and is delivered through a canal 180.

In order to regulate the output of the 110 pump the casing 10 is swung around the center of block 30 by means of the screws

140 and is guided during this movement on the periphery of the segment 120. By these swinging movements pinion 80 will be removed from or approached to the pinion 90 and according to the distance between the axes of these pinions a greater or lesser quantity of liquid caught in the spaces between the teeth which are turning in the direction indicated by the arrows in Fig. 5 10 will reflow again into the suction chamber of the pump.

By unscrewing the pressure screw 60 the cover and the casing may both be removed without any tool. After the casing 10 has 15 been removed the pinion 80 may be taken out by an axial pressure by hand and the segment 120 may be removed from the block 30 so as to uncover the teeth of the pinion 90 which is integral with the trunnion 10. 20 Then this latter pinion can be withdrawn after having removed the rope pulley 110.

It must be stated that by regulating the output of the pump also the conditions of tightness of the stationary pinion 90 are 25 changed because by means of the screws 140 the removable segment 120 is swung around the pin 130 which means that the walls of the cavity are pressed against the teeth of said pinion 90. Regarding the other pinion 30 80 the effect of gearing will be to press said pinion into the cavity of the casing.

What I claim is:

1. In a gear wheel pump for furnishing viscose threads of a predetermined thickness 35 and in combination a casing having a circular lodging, a bracket fitted slidably into said lodging, a set of pinions, the first of them guided within an eccentric cavity of said casing and the second eccentrically 40 lodged within and partly surrounded by said bracket and means adapted to turn said bracket within its lodging and to regulate thereby the distance between the two pinions and the output of the pump.

45 2. In a gear wheel pump of the kind described and in combination a casing having

a circular lodging, a bracket fitted slidably into said lodging, a set of pinions, the first of them guided within an eccentric cavity of said casing and the second eccentrically 50 lodged within and partly surrounded by said bracket, a block confining the hollow of said casing and forming the support of said second pinion and adjusting screws mounted on said block and bearing on arms fast to said casing as means for turning said bracket within its lodging in order to regulate the distance between the two pinions and thereby the output of the pump.

3. In a gear wheel pump and in combination, a box open on one side, a cover fitting tightly said open side of the box, a set of pinions tightly enclosed between box and cover, a trunnion integral with the first of said pinions and lodged in the cover, a driving wheel fast to said trunnion on the outside of said cover, and a rotative bracket having a cavity surrounding tightly the second pinion and having its axis of rotation arranged eccentrically to the axis of rotation 65 of the second pinion.

4. In a gear wheel pump and in combination, a box and a cover having a pin engaged to said box, a casing open on both sides and fitted tightly between box and 75 cover, a segment in a cavity of said casing and serving as guide to it and pivoted on said pin of the cover, a set of pinions the first embedded eccentrically in a cavity of said casing and the second embedded in a 80 cavity of said segment, two tie rods secured to said box, a cross-bar carrying a pressure screw for said cover attached to said tie rods, lugs cast to said casing and adjusting screws held in swellings of said tie rods and bearing on said lugs of the casing so as to be 85 adapted to regulate the output of the pump by changing the distance between the centers of said pinions.

In testimony whereof I affix my signature.

ANDRÉ BECHLER.
